(57) **CLAIM**

The combination infant seat carrier and detachable storables stroller support assembly, as shown and described.

DESCRIPTION

The characteristic features of this design reside in the distinctive appearance of an assembled combination infant seat carrier and detachable storables stroller support assembly having detachable storables components including, as a component, an infant seat carrier configured for separate use in a passenger vehicle.

FIG. 1 is a top, front and right side perspective view of a combination infant seat carrier and detachable storables stroller support assembly;

FIG. 2 is a bottom, rear and right side perspective view of a combination infant seat carrier and detachable storables stroller support assembly of FIG. 1;

FIG. 3 is a front elevational view of a combination infant seat carrier and detachable storables stroller support assembly of FIG. 1;

FIG. 4 is a bottom plan view of a combination infant seat carrier and detachable storables stroller support assembly of FIG. 3;

FIG. 5 is a top plan view of combination infant seat carrier and detachable storables stroller support assembly of FIG. 3; FIG. 6 is a right side elevational view of a combination infant seat carrier and detachable storables stroller support assembly of FIG. 3;

FIG. 7 is a left side elevational view of a combination infant seat carrier and detachable storables stroller support assembly of FIG. 3; and,

FIG. 8 is a top, front and right side exploded perspective view of a combination infant seat carrier and detachable storables stroller support assembly of FIG. 1.

The broken lines showing the operative or assembled positions of the detachable storables components of the combination infant seat carrier and detachable storables stroller support assembly relative to each other are for illustrative purposes only and form no part of the claimed invention.
